SLEEVE-TYPE MAGAZINE CATCH AND DUST COVER FOR FIREARMS

Frederick P. Reed, Ludlow, Mass., assignor to the United States of America as represented by the Secretary of the Army

Application September 29, 1959, Serial No. 843,316

5 Claims. (Cl. 42—18)

(Granted under Title 35, U.S. Code (1952), sec. 266)

The invention described herein may be manufactured and used by or for the Government for governmental purposes without the payment of any royalty thereon.

This invention relates to automatic firearms and more particularly to latch devices for releasably retaining a magazine to the receiver and for selectively covering the openings therein.

It is the object of this invention to provide for firearms having cylindrical receivers and which are supplied with cartridges from a box-type magazine, a combined magazine latch and dust cover device for releasably securing the magazine to the receiver and selectively covering the receiver openings which receive the magazine and which permit ejection of the spent cartridge cases.

The specific nature of the invention as well as other objects and advantages thereof will clearly appear from a description of a preferred embodiment as shown in the accompanying drawings in which:

Fig. 1 is a fragmentary cross-sectional view of a receiver with the magazine catch positioned to secure the magazine to the receiver and to uncover the cartridge ejection port;

Fig. 2 is a view taken along line 2—2 of Fig. 1;

Fig. 3 is a view taken along line 3—3 of Fig. 1;

Fig. 4 is a view similar to Fig. 2 but with the catch rotated into position for installation and removal of the magazine;

Fig. 5 is a view similar to Fig. 3 but with the catch rotated to the position noted in Fig. 4;

Fig. 6 is a view similar to Figs. 2 and 4 but with the catch rotated to cover the ejection and magazine ports;

Fig. 7 is a view similar to Figs. 3 and 5 but showing the catch rotated to the position noted in Fig. 6; and

Fig. 8 is an exploded view of the catch, receiver and magazine.

Shown in the figures is a cylindrical firearm receiver 12 provided with a magazine port 14 through the underside thereof for receiving a box-type magazine 16 and with an ejection port 18 through the upper side for expelling fired cases. A lip 20 is fixed to each of the front and rear sides of magazine 16 adjacent to but spaced from the tops of such sides so as to extend outwardly at right angles therefrom. The lips 20 are received partially into corresponding recesses 22 formed in the outside wall of receiver 12 when the portion of magazine 16 above such lips is inserted into magazine port 14.

Magazine 16 is releasably secured against displacement from receiver 12 by a cylindrical sleeve-like catch 24 which is mounted over the receiver for rotation therearound. Catch 24 is provided with an ejection opening 26, which coincides with ejection port 18 when rotated thereto, and a magazine opening 28 by which magazine port 14 is exposable for installation and removal of magazine 16.

Magazine opening 28 is T-shaped in configuration and includes a longitudinal mouth portion 30 having approximately the same dimensions as the top of magazine 16

2

including lips 20, so that such lips may be insertable therethrough into recesses 22, and a clearance portion 32 having substantially the same dimensions as the top of the magazine, not including the lips, extending symmetrically from the right side of the mouth portion. The portions of catch 24 extending along the front and rear sides of clearance portion 32 from mouth portion 30 form latch portions 34 which are pressed outwardly to a larger diameter and thereby are movable under the lips 20 which, as noted hereinbefore, are only partially received by the recesses 22 and thereby extend outwardly beyond the perimeter of receiver 12. Thus, when catch 24 is rotated to where mouth portion 30 uncovers magazine port 14, magazine 16 is insertable thereinto and clearance portion 32 permits further rotation of catch 24 in a clockwise direction after installation of the magazine so that latch portions 34 may be moved under the lips 20 to releasably secure the magazine to receiver 12.

Clearance portion 32 extends sufficiently from mouth portion 30 so that catch 24 may be rotated to the three positions hereinafter defined. Catch 24 is limited as to angular displacement and is prevented from forward displacement, when magazine 16 is removed, through the cooperation of a pin 36 extending radially from receiver 12 with a cutout portion 38 formed in the front end of the catch. Cutout portion 38 is defined by a pair of end walls 40 and a connecting rear wall 42. The contact of pin 36 with the end walls 40 limits the rotation of catch 24, and forward displacement of the catch is prevented by the sliding engagement of the pin with rear wall 42. Ejection opening 26 is spaced relative to magazine opening 28 and pin 36 is so disposed relative to cutout portion 38 that, when magazine 16 is removed from receiver 12 and pin 36 is in contact with one of the end walls 40, catch 24 is in the first of the three aforementioned positions with ejection port 18 and magazine port 14 covered by catch 24 to prevent dust and any other foreign matter entering the receiver as is shown in Figs. 6 and 7.

When catch 24 is in the second one of the three positions, the latch portions 34 are disposed under the lips 20 to secure magazine 16 to receiver 12 and ejection port 18 is covered, and when in the third position, shown in Figs. 1, 2 and 3, pin 36 is in contact with the opposite one of the end walls 40, the latch portions 34 remain disposed under the lips 20 and ejection opening 26 is in registry with ejection port 18 to permit the ejection of fired cases from the receiver. When catch 24 is rotated intermediate the first and second positions, as shown by Figs. 4 and 5, mouth portion 30 is in registry with magazine port 14 so that magazine 16 may be installed in or removed from receiver 12.

Catch 24 is indexable in the three positions through the cooperation of a detent spring 44 with three notches 46 pressed outwardly from the inside of the catch at the rear end thereof. Each of the notches 46 is terminated at the front end by a wall 47. Spring 44 is of the leaf type and is mounted within a mating recess 48 in the outside of receiver 12 so as to bow outwardly therefrom. One end of spring 44 is fixedly attached to receiver 12 as by spot welding, and provided approximately central of the length of the spring is a protruding detent 50 which is of inverted V-configuration so as to be receivable by one of the three notches 46 when in registry therewith. Besides releasably indexing catch 24 in the three positions, detent 50 also secures the catch against rearward displacement when the magazine is removed from receiver 12 through the engagement of the detent with front wall 47 of the selected one of the notches 46. Catch 24 is removable from receiver 12, when the magazine is removed therefrom, by rotating the catch until detent 50 is rotated out of engagement with any of the notches 46 and is slidably engaged with the inner sur-

face of the catch which is freed thereby for rearward removal.

From the foregoing it is clearly apparent that there is provided herein a magazine catch of simple and rugged construction which also serves to selectively close the ports in the receiver to prevent dust or other foreign matter entering thereinto.

Although a particular embodiment of the invention has been described in detail herein, it is evident that many variations may be devised within the spirit and scope thereof and the following claims are intended to include such variations.

I claim:

1. For a firearm having a cylindrical receiver provided with an ejection port and a magazine port for receiving a magazine, a combined magazine latch and dust cover device including a cylindrical catch rotatably mounted around the receiver and disposed thereover to close the ejection port and the magazine port, means in said catch for selectively exposing the ejection and magazine ports when in registry therewith, and cooperating latch means on the magazine and said catch for releasably securing the magazine to the receiver by rotation of said catch.

2. For a firearm having a cylindrical receiver with an ejection port and a magazine port for receiving a combined magazine latch and dust cover device including a cylindrical catch rotatably mounted around the receiver and disposed thereon to cover the ejection port and the magazine port, a magazine opening disposed in said catch for registry with the magazine port when rotated thereto to permit insertion of the magazine thereinto, cooperating latch means on the magazine and said catch for selectively securing the magazine to the receiver by rotation of said catch, and an ejection opening disposed in said catch for selective registry with the ejection port while the magazine is secured to the receiver by said latch means.

3. For a firearm having a cylindrical receiver provided with an ejection port and a magazine port for receiving a box-type magazine, a combined magazine

latch and dust cover device including a lip extending outwardly from each of the front and rear sides of the magazine, a cylindrical catch rotatably mounted around the receiver and disposed thereon to close the ejection port and the magazine port, a magazine opening disposed in said catch for selective registry with the magazine port, said magazine opening including a mouth portion dimensioned to permit insertion of the magazine into said magazine opening and passage of said lips through said catch and a clearance portion extending from said mouth portion to permit rotation of said catch after installation of the magazine, latch portions disposed along the sides of said clearance portion for sliding contact with said lips to secure the magazine to the receiver, and an ejection opening disposed in said catch for selective registry with the ejection port in the receiver when said latch portions are in contact with said lips.

4. The combined latch device and dust cover as recited in claim 3 and including means for selectively indexing said catch to and from three positions comprising a first position wherein said magazine opening is out of registry with the magazine port in the receiver and said ejection opening is out of registry with the ejection port in the receiver to prevent dust or any other foreign matter entering thereinto, a second position wherein said clearance portion of said magazine opening is in registry with the magazine port and said latch portions are in contact with said lips of the magazine when installed in the magazine port and said ejection opening is out of registry with the ejection port, and a third position wherein said ejection opening is in registry with the ejection port and the magazine is secured to the receiver by contact of said latch portions with said lips.

5. The combined latch device and dust cover as recited in claim 4 wherein said indexing means includes a bowed leaf spring mounted to the receiver, a detent protruding from said spring, and three notches formed in said catch to selectively receive said detent and disposed in said catch to receive said detent when said catch is in a corresponding one of the three positions.
